UNITED STATES PATENT OFFICE.

ROBERT DUFFUS, OF LUTTERWORTH, ENGLAND.

FOUNDRY MOLDING MACHINE.

Application filed September 3, 1921. Serial No. 498,300.

To all whom it may concern:

Be it known that I, ROBERT DUFFUS, a subject of the King of Great Britain, residing at Gladstone Road, Lutterworth, in the 5 county of Leicester, England, have invented new and useful Improvements in Foundry Molding Machines, of which the following is a specification.

This invention has reference to certain improvements in or in connection with molding, pressing and the like machines used in foundry work and has for its primary object to provide for a deep, accurate and variable draw.

15 A further and no less important object aimed at is simplicity, both in construction and operation whereby not only has the improved machine a comparatively low first cost but it lends itself for use with unskilled 20 labour.

When, as it is claimed, these advantages are accompanied by a very high standard of efficiency, it will be appreciated that the introduction of the improved machine is of 25 considerable importance to the industrial world, since castings, which hitherto have been made by hand, can now easily be turned out in large numbers.

The present invention while more particularly designed for molding and pressing machines of the turn-over pattern plate type with hand operated pit draft mechanisms suitable for small repetition work is also applicable to larger machines of the class 35 operated by power.

According to this invention the vertical shafts by which the pattern plate is raised and lowered, instead of being operated from their bottom extremities by short toggles are 40 raised and lowered by comparatively long connecting rods hinged at their upper ends to an intermediate part of said shafts whilst their lower ends are connected with long cranks on the horizontal crank shaft. By 45 this means the effort required in raising and lowering the pattern plate is considerably reduced while at the same time a much deeper draft is possible than hitherto.

The improved machine also embodies further useful features which will be herein-after described with reference to the accompanying drawings wherein,

Figure 1 is a transverse sectional view on the line *a*—*b* of Figure 2 of a molding machine constructed according to this invention, the vertical shaft being shewn in its

low and high positions in full and dotted lines respectively.

Figure 2 is a part sectional side view of the complete machine with the vertical 60 shafts in the bottom position and the pattern plate brackets occupying a horizontal position.

Figure 3 is a part view of the upper ends of the vertical shafts shewing the pattern 65 plate brackets swung into a vertical position.

Figure 4 is a detail end view of the trunnion head carrying the trip stop.

Throughout the drawing like parts are designated by similar reference characters. 70

Referring to the drawing, 2, 2 represent the vertical shafts carrying trunnion heads 3, 3 at their upper ends in which the pattern plate brackets 4, 4 are rotatably mounted.

The said shafts are mounted so as to be 75 free to reciprocate vertically in bearings in standards 5, 5 which are bolted down to a bed plate or frame 6 and are provided with removable inspection plates 7, 7 to facilitate access to the intermediate portions of said 80 shafts.

The shafts 2, 2 are operated within the standards from a horizontal shaft 8 mounted loosely in bearings in the bed plate 6, by means of cranks 9, 9 which are keyed to said 85 shaft. The free ends of the cranks are operatively and severally connected with the vertical shafts at an intermediate point in the latter by means of connecting rods 10 and shaft clamps 11.

The horizontal shaft 8 is turned to cause the cranks to raise and lower the vertical shafts by means of a hand-lever 12 secured thereto at one end and working in a notched quadrant 13 with which a pawl 14 on the 95 lever is adapted to engage to lock the shaft and levers in any desired position according to the amount of draw required. The pawl can be arranged for operation from the handle of the lever as shewn.

The weight of the shafts 2, 2 and the parts carried thereby is counterbalanced by means of weights 15 which are suspended by chains or wire ropes 16 the upper ends of which pass over pulleys 17 and are secured to the 105 shaft clamps 11. The pull on the chain is as will be seen substantially parallel with the vertical shafts so that lateral stresses are avoided.

Alternatively, the lower ends of the vertical shafts may be supported by stirrup bars suspended by chains or wire ropes passed

over pulleys in the standards and having their free ends attached to counter-weights.

The pattern plate (not shewn) is adapted to slide between the slotted portions 4^a, 4^a, 5 of the brackets 4, 4 and to be secured thereto in any readily releasable manner as by pins or bolts passed through the holes 18.

In order to provide for a perfectly accurate draw which is particularly desirous 10 in the case of a deep draft means are provided for locking the pattern plate in a plane truly at right angles to the axes of the vertical shafts. For this purpose one of the trunnion heads 3 has laterally projecting 15 arms 3^a one of which carries a trip stop 19 loosely pivoted thereto on a horizontal axis whilst the other is furnished with a locking catch 20 arranged to turn about a vertical pivot. A stop 19 has a shouldered end 20 which, as shewn in Figure 1, closely overhangs the end of the arm 3^a to which the stop is pivoted. The free end of the said arm is rounded at 3^b, see Figure 4, to allow 25 the stop 19 to make a quarter turn on its pivot from the horizontal. Each end of the adjacent bracket 4 carries a projecting lug 21 one of which when the pattern plate is horizontal rests on the stop 19 whilst the other lug is engaged by the catch 20 the effect of which is to lock the plate firmly 30 against the stop 19. When it is desired to turn the plate over the catch 20 is disengaged from the lug 21 on the adjacent end of the bracket 4 and the plate is then revolved about its trunnions in the direction 35 of the arrow (Figure 1) until the lug 21 which was formerly engaged by the catch 20 has tripped by the stop 19, when the plate is brought back to a horizontal position with 40 the lug 21 taking a seating on top of the stop 19 against which it is firmly locked by turning the locking catch 20 into engagement with the lug 21 on the opposite end of the bracket 4.

45 The bed plate carrying the standards is provided with the customary tram rails (not shewn) for the molding boxes or the tracks by which they are introduced into and removed from the machine.

50 If desired also the machine may be provided with a presser head of any suitable design.

The type of machine shewn in the accom-

panying drawings is for medium and small size machines and as will be seen do not require a pit or special foundation as would be the case for the large size machines. Otherwise for large, medium or small sizes the constructional features are as hereinbefore described.

I claim:

1. Foundry molding machine comprising in combination a pair of rotatable brackets independently mounted on horizontal axes and adapted to receive the pattern plate between them, trunnion heads carrying said brackets, connecting rod and crank mechanism for raising and lowering said heads, laterally projecting lugs on the opposite ends of one of said brackets, a stop pivoted at one side of the adjacent trunnion head and having a limited rotary movement from the horizontal to the vertical and adapted in the former position to form an abutment for one of the said lugs, a locking catch pivoted at the other side of the same trunnion head and adapted to be moved into engagement with the other of said lugs on the adjacent end of the pattern plate when the latter is brought down to the horizontal position against the said stop.

2. Foundry molding machine comprising in combination a pair of rotatable brackets independently mounted on horizontal axes and adapted to receive the pattern plate between them, trunnion heads carrying said brackets, means carried by one of said brackets and by the adjacent trunnion head for locking the pattern plate in a horizontal position, vertical shafts carrying said trunnion heads at their upper ends, hollow standards supporting said shafts, a bed plate carrying said standards, a horizontal shaft rotatably mounted in said bed plate, cranks on said shaft projecting vertically below said shafts, clamps on said shafts, rods arranged parallel with said shafts and connecting the cranks with said clamps, a pulley mounted in the upper end of each standard above said clamp, and a cable connected to said clamp and passing upwardly parallel with the vertical shaft over the said pulley and thence downwards beneath the bed plate and having a weight attached thereto.

ROBERT DUFFUS.
